METHOD OF MANUFACTURING PAPER CLIPS

Howard D. Randall, Cincinnati, Ohio

Original application November 1, 1933, Serial No. 696,237. Patent No. 2,047,129, dated July 7, 1936. Divided and this application March 15, 1935, Serial No. 11,307

4 Claims. (Cl. 140—82)

This invention relates to a novel type of paper clip or the like and a method of manufacturing same.

The present application is a division of my 5 United States Letters Patent of July 7, 1936, No. 2,047,129, filed November 1, 1933.

An object of the invention is to provide a very inexpensive and effective paper clip or the like, distinguishable from others by reason of its spiral 10 formation and certain advantages resulting from such formation.

Another object of the invention is to provide a novel type of paper clip or the like, so constructed that it cannot tear or otherwise damage sheets of 15 paper held thereby, when the clip is removed from such sheets.

A further object of the invention is to provide a novel paper clip or the like having inner and outer convolutions with different gripping 20 strengths or compressive forces, whereby either thin or thick stacks of sheets may be effectively clipped without springing the clip out of shape and detracting from its continued usefulness.

The foregoing and other advantages are attained by the means described herein and disclosed in the accompanying drawing, in which:

Fig. 1 is an enlarged plan view of the novel clip of the invention.

Fig. 2 is a side view of the clip of Fig. 1, taken 30 on line 2—2 of Fig. 1.

Fig. 3 is a plan view of a length of wire, which may be either round or angular in cross-section, and from which the clip is formed.

Fig. 4 is a plan view showing the wire as it is 35 initially bent into spiral formation during manufacture of the clip.

Fig. 5 is a side view showing how the spiral formation of Fig. 4 is flattened or swaged to produce the ultimate formation of the clip.

Fig. 6 is a plan view of a modification.

The clip illustrated in Figs. 1 and 2 is constituted of a single piece of flattened resilient wire of a proper length to form a spiral shape having two or more convolutions 7, 8 and 9. Although 45 any reasonable number of convolutions or spiral turns of wire may constitute the clip, it is found that from three to six thereof provides a clip which satisfactorily holds together the sheets of all ordinary sized stacks or compilations of sheets.

As is clearly indicated in Fig. 2, the finished 50 clip is substantially flat, and has a rounded terminal end 10 which is easily formed during the single stamping or flattening operation with which the entire clip is made. The inner terminal end of the material forming the clip is indi-

cated at 12, and this end may also be rounded if desired.

In manufacturing the clip of this invention a length of resilient wire or the like 13, which may be either round or angular of cross-section, is 5 bent into spiral formation as shown in Fig. 4, and thereafter it is placed between the pressing die elements 14 and 15 which flatten the spirally wound wire to the extent indicated in Fig. 2. The flattening of the wire, or the heat generated 10 by the swaging or flattening operation, have the effect of changing the molecular structure of the wire, thereby increasing the resiliency of the clip material and rendering the clip more effective and satisfactory than the initially formed spiral 15 shape of Fig. 4. In other words, a superior product results from the swaging treatment.

Either before or after the swaging operation, the material of the clip may, if desired, be bonderized or treated with a suitable coating 16 containing a gritty or frictional material adapted to provide a frictional finished surface upon each of the convolutions of the clip. This treatment, however, is not essential to the proper functioning of the clip, and may be omitted if desired.

Clips made in accordance with the above teaching are found to tenaciously hold a thin stack of sheets when the stack is gripped between the inner convolutions, while thicker stacks may more readily be held by the outermost spirals or convolutions. It is not to be understood that the thinner stacks of sheets must necessarily be inserted between the inner convolutions, for the clip is sufficiently resilient and forceful to hold the thinner stacks between any of the spiral turns.

The clip of Fig. 6, instead of being formed generally circular, is made angular in general contour, and it may be produced by the same method as is employed in producing the clip of Fig. 1. The disclosure of Fig. 6 suggests clips of square 40 or other polygonal shapes, made in accordance with the above explained method.

What is claimed is:

1. The method of manufacturing a thin flat paper clip having a high degree of resiliency and 45 holding power, which method comprises the steps of bending into a spiral having spaced convolutions, a length of light gauge wire which initially offers but little resistance to manual bending, and then swaging the spiral formation between flat 50 surfaces with sufficient force to flatten opposite sides thereof to result in a thin spiral ribbon formation having all points on its convolutions disposed in a common plane.

2. The method of manufacturing a thin flat 55

paper clip having a high degree of resiliency and holding power, which method comprises the steps of bending into a spiral having spaced convolutions, a length of light gauge wire which initially offers but little resistance to manual bending, and then flatly swaging the spiral formation thereby produced, with sufficient force to change the wire convolutions to flat ribbon convolutions, all points of which are disposed in a plane, and to simultaneously enhance the resiliency of the convolutions by reason of the change of molecular structure of the wire resulting from the swaging force.

3. The method of manufacturing a thin flat paper clip having a high degree of resiliency and holding power, which method comprises the steps of bending, into a substantially spiral shape having spaced convolutions, a length of light gauge wire which initially offers but little resistance to manual bending, and then flattening the spiral formation thereby produced, with sufficient force to change the wire convolutions to flat ribbon convolutions, all points of which are disposed in

a plane, and to simultaneously enhance the resiliency of the convolutions by reason of the change of molecular structure of the wire resulting from the flattening operation.

4. The method of manufacturing a thin flat paper clip having a high degree of resiliency and holding power, which method comprises the steps of bending a length of light gauge wire, which initially offers but little resistance to manual bending, to a shape which comprises convolutions terminating interiorly and exteriorly of the clip, and thereafter flattening the shape thereby produced, with sufficient force to change the wire convolutions to thin, flat, coplanar ribbon-shaped convolutions such as to yield upon application of the clip to a compilation of paper sheets, the flattening force serving to enhance the resiliency of the clip by reason of the change of molecular structure of the wire resulting from the flattening operation.
